CARRIER FOR BRAIDING MACHINES

William E. Cook, West New Brighton, N. Y.

Application September 26, 1934, Serial No. 745,502

12 Claims.

(Cl. 96—13)

The invention relates to carriers for braiding machines, and more particularly to a carrier of the type having a vertically extending spindle for the reception of the cop.

Carriers of the type to which the invention relates are mounted upon the top plate of a braiding machine, and are moved by a series of gears in a sinuous path about the axis of the plate as determined by cam grooves in the plate. When forming a tubular braid, the carriers move throughout a full circle, but when forming a flat braid, they have movement throughout only a portion of the circle and then their movement is reversed. A plurality of carriers are used upon such braiding machines, and carriers adjacent each intersection of the cam slots closely approach each other, so that in the event of ballooning of the yarn there is likelihood of the yarn from one cop becoming entangled with parts of a closely adjacent carrier, and this likelihood is greatly increased when the wear upon the cam slots, or upon the shoe upon the carrier co-operating therewith, occurs to an extent to permit substantial side sway of the carrier.

The in and out movement of the carriers, or their radial component in relation to the axis of the top plate, as they follow the sinuous cam grooves, imparts to the yarn from each cop a necessary oblique trend axially of the top plate because of the lineal traverse of the previously formed braid, or of the material upon which the braid is being formed, the timed radial movement of succeeding carriers causing the entwining of the yarn after it is withdrawn from the cops on these carriers in a manner well known.

A carrier of the type to which the invention relates embodies therein a vertically reciprocating weight, generally called a traveler, acting in a bight of the yarn between the cop and the lead-off eye of the carrier. This traveler is provided to take up slack in the yarn during movement of the carrier toward the axis of the top plate, and to rapidly pay out yarn with movement of the carrier away from said axis, during which time yarn is drawn from the cop. This is to prevent what is known as "whipping" of the yarn between the carriers and the braid being formed. In some carriers, tension devices are used to supplement the traveler in preventing whipping, by retarding the run of the yarn.

In the type of carrier described in my co-pending application Serial No. 719,249, a buffer spring is provided which develops resistance to the upward movement of the traveler toward the limit of this movement, to ensure a rapid taking up of

slack and to aid in the withdrawing of yarn from the cop. This buffer spring also has a tendency to equalize the tension applied to the yarn when forming the braid. In the said carrier, a special form of brake plate is used which acts directly upon the yarn upon the cop to prevent possible overrunning of the cop in a manner to create slack between the cop and the traveler.

When undue wear has not occurred upon the shoe of the carrier and the cam slot along which it has movement, the carrier of my aforesaid application has been found to give highly satisfactory results. When the parts are worn, however, swaying of the carrier at times results in the bringing of the run of the yarn between the traveler and the lead-off eye of one carrier into engagement with parts of another carrier, thus causing the breakage of the yarn due to the pull thereon with opposite travel of the two carriers. This results from slight, momentary "ballooning" of this reach of the yarn resulting from a rapid upward movement of the traveler.

Cops are differently wound. In some spirally wound cops, two convolutions occur along the length of the cop. Others may have three or four convolutions. When drawing the yarn from the cop, the point at which it leaves will, at different times, extend from the extreme top to the extreme bottom of the cop. The usual practice in carriers is to provide an eye intermediate the top and bottom of an upright along which a traveler has movement, thus causing a constant change and wide variance in the angle of the yarn from the cop to this eye. Toward the bottom of the cop, with some yarns, there is a tendency of the yarn to escape from the lower edge of the winding upon the cop and become entangled with the parts of the carrier below the cop and thus cause breakage of the yarn.

By my present invention, I provide a carrier wherein the reach of the yarn between the traveler and the lead-off eye is so confined by a collapsible member as to prevent its engagement with other carriers during the operation of a braiding machine. One end of the collapsible member is engageable by the traveler and the other end is secured adjacent the lead-off eye. By this construction, a free run of the yarn is permitted, and the desired tautness in the yarn, by other agencies in the carrier, may be secured.

As will more fully appear hereinafter, the collapsible confining member is preferably in the form of a long spiral spring, thus combining in this member the three-fold function of a restraining means preventing ballooning of the yarn, a

resistance to movement of the traveler ensuring a desired tautness in the run of the yarn from the carrier to the braid, and an accelerator for reversing the movement of the traveler to minimize whip of the yarn between the lead-off eye and the braid. When such a spring is used, a guide therefor is provided to limit bulging of the spring. With this construction, there is no danger of the yarn becoming entangled with the coils of the spring, since the portion thereof within the spring is always sufficiently taut to avoid slack which might be engaged between succeeding coils.

In conjunction with the yarn confining means above referred to, I provide an upright upon which the traveler is mounted, having therein a vertically extending elongated slot, thus permitting the yarn in passing through this upright to follow the traveler within substantially the maximum range of its movements, and permitting the yarn to run from the cop to the traveler without excessive change in the angularity of the reach thereof between the traveler and the cop. This feature is particularly desirable in connection with a carrier of the type in which a retard or brake plate is spring pressed against the surface of the cop, since likelihood of breakage of the yarn due to weak spots therein is reduced to a minimum, and there is greater uniformity in the resistance to the run of the yarn where there is no abrupt bend thereof, as when an eye is positioned intermediate the top and bottom of the carrier upright.

I also provide in a carrier embodying the invention, a retard or brake plate of a vertical length including a substantial portion of the length of the cop, thus minimizing likelihood of the loosening of the convolutions of the yarn upon the cop and the consequent bunching thereof in a manner to interfere with the free run of the yarn or to permit a run thereof without restraint from said plate.

In order to equalize the resistance to the turning movement of the cop, the brake plate is so formed that with a decrease in the diameter of the cop, the contact area between the brake plate and the surface of the cop will be progressively reduced in order to compensate for the increase in speed of the cop as it lessens in diameter. This feature is an incident to the carrier structure of my aforesaid co-pending application.

With the pivotal movement of the plate, the effective leverage at which it acts upon the cop is diminished. This solely is not relied upon to secure a desired approximate uniformity in the resistance to the turning movement of the cop, the brake plate, as stated, being so curved as to secure the variable contact area above referred to.

To prevent the slippage of the lowermost convolutions of yarn upon the cop from the lower edge of the wound portion of the yarn, and the entanglement of this yarn with the mechanisms of the carrier below the spool of the cop or between the spool and the spindle, I provide a cup, the top of which is positioned above the bottom of the cop so as to impart a lift to the yarn being drawn from adjacent the bottom of the cop. This cup also prevents the yarn falling a sufficient distance below the bottom of the cop to come into contact with the parts of the carrier below.

The invention consists primarily in a carrier for braiding machines embodying therein a base provided with a vertical spindle adapted to have a cop rotatably mounted thereon, and means

whereby travel may be imparted to the carrier, an upright paralleling said spindle having a vertically elongated opening therethrough for the run of the yarn, and a lead-off eye adjacent the top thereof, and means for controlling the run of the yarn from the cop and for applying tensioning stresses to the yarn embodying therein a traveler slidably mounted upon said upright for movement along the portion of said upright having said elongated opening therein toward and from said lead-off eye about which the yarn passes in its run from said opening to said lead-off eye, and a collapsible confining member at one side of said upright, one end of which is engageable by said traveler, and the other end of which extends to adjacent said lead-off eye; and in such other novel features of construction and combination of parts, as are hereinafter set forth and described, and more particularly pointed out in the claims hereto appended.

Referring to the drawing,

Fig. 1 is a front view of a carrier embodying the invention;

Fig. 2 is a side view thereof;

Fig. 3 is a back view thereof;

Fig. 4 is a section on the line 4—4 of Fig. 1; and

Fig. 5 is a condensed view of the yarn threading device.

Like numerals refer to like parts throughout the several views.

In the embodiment of the invention shown in the accompanying drawing, the carrier has a base 10 provided with parallel flanges 11 and 12 adapted to embrace the opposite edges of the sinuous cam slot in the top plate of a braiding machine, 35 and a bottom pivot 13 adapted to be engaged by slots upon the actuating gears of the braiding machine.

Carried by said plates is a vertical spindle 14 upon which the core 15 of a cop 16 of yarn is 40 adapted to be rotatably mounted. The core, as shown in the drawing, is of the headless type, although such head ends may be used if desired. The cop is of the side draw type having a standard oblique winding.

Intermediate the flanges 11 and 12 is the usual shoe 17 co-operating with the edges of the cam slot to impart sinuous movement to the carriers. This means imparting travel to the carriers is old and well known in the art.

Carried by the plate 11 is an upwardly extending upright paralleling the spindle 14. In the form of the invention shown, this upright is formed of two round rods 18 and 19 spaced apart to form an elongated slot through which the 55 yarn may pass and follow the traveler in its vertical movement in a manner to be hereinafter referred to.

To define the length of the slot in its relation to the movement of the yarn, I provide upper and lower stops 20 and 21 extending across the space between said rods, the ends of which do not extend beyond the rods 18 and 19 to an extent to interfere with the free movement of the traveler, particularly as to its downward movement. This 65 is necessary to permit the actuation of the automatic stop mechanism commonly used in braiding machines.

Surmounting the rods 18 and 19 is a head fitting 22 carrying a lead-off eye 23 in a position intermediate the axis of said rods and at one side thereof. Extending from the head fitting 22 is a small guide rod 24, the lower end of which is secured to the base 10 in any desired manner. To control the run of the yarn from the cop and ap-

ply tensioning stresses thereto, I provide means including therein a traveler 25 slidably mounted upon the upright formed by the rods 18 and 19. This traveler is of the usual construction having a recess 26 at a point intermediate the rods 18 and 19, and shoes 27 bearing upon the edges of the upright and guiding the movement of said traveler.

In addition to the use of the traveler 25 for the purpose described, I provide a coiled spring 28, one end of which extends to adjacent the head fitting 22 and the other end of which bears upon the top of the traveler 25. This spring is of light tension and its coils encircle the small guide rod 24, which is positioned rearwardly of the traveler in a position substantially centrally of the space between the rods 18 and 19. The diameter of the spring is considerably larger than that of its guide rod 24 affording space for the run of the yarn from the traveler to the lead-off eye 23. This run of the yarn through the coils of the spring confines this reach of the yarn in a manner to avoid all possibility of ballooning, collapsibility of the spring as a whole permitting free reciprocatory movement of the traveler. The guide rod 24 prevents lateral bulging of the spring as it is being collapsed.

While collapsible means of a different form may be used independently of or in conjunction with the spring 28, actual practice has demonstrated that the spring 28 alone affords an adequate safeguard against ballooning of the yarn and that there is little or no likelihood of the entanglement of the yarn in the coils of the spring, since the portion of the reach of the yarn confined within the spring is, during the collapsing of the spring, held taut by the traveler and other parts of the means controlling the run of the yarn from the cop and applying tensioning stresses thereto.

The main function of the traveler 25 is to take up slack in the yarn while the carrier is having a component of movement toward the braid being formed, and to feed out yarn while the carrier is having an outward component of movement, and incidentally to assist in drawing yarn from the cop as it is required during such outward movement of the carrier. The spring 28 assists the traveler in both of these functions. This relieves the yarn from excessive or irregular stresses both in paying out the yarn through the lead-off eye and in drawing yarn from the cop.

In withdrawing yarn therefrom, the cop is turned by successive short impulses and it is desirable to limit the amount of yarn withdrawn to that which can be readily taken up by reciprocatory movement of the traveler so as to avoid the creation of slack between the traveler and the cop. To prevent unrestricted turning movement of the cop, I mount upon the base 10, a rod 29 encircled by a torsion spring 30, one end of which is secured to said rod and the other end of which bears upon a brake plate 31 pivotally mounted upon said rod. This plate 31 is of sheet metal and is formed in an irregular curve so that the area of contact between this plate and the yarn upon the cop will be greatest when the cop is at its maximum diameter and will progressively decrease with the lessening of the diameter of the cop.

This arrangement is for the purpose of developing a predetermined braking action by the plate 31 when the cop has the slowest and shortest movement in drawing a given quantity of yarn therefrom, and to substantially maintain this breaking action by decreasing the contact area

as the speed of movement of the cop increases with its lessening diameter. It is unnecessary to form the plate 31 with any great accuracy so as to establish a fixed ratio between the braking area and the speed of the cop, the construction and mode of operation of the carrier not lending itself to any such nicety. As the diameter of the cop decreases, however, the effective leverage at which the brake plate acts and the lessening of the tension of the spring 30 do not reduce the braking action sufficiently to develop the desired resistance to the turning of the cop with increased speed thereof with such lessening of its diameter. Hence, by forming the plate as described, the resistance to turning movement of the cop may be maintained approximately uniform by reducing the braking area in substantial proportion to the increase of the speed of the cop.

No friction lining for the brake plate is required since this plate engages the yarn which is sufficiently soft to develop the desired frictional resistance between it and the plate.

In obliquely wound cops, there is a tendency for the yarn in its run from the surface of the cop to become entangled with other convolutions of the yarn of the cop, by reason of the falling of the convolutions of the yarn in case of looseness in the winding of the yarn. To minimize likelihood of this occurring, I preferably make the plate of a height to overlay the yarn throughout a substantial portion of the length of the cop, thus tending to confine the convolutions of the yarn so that with the run thereof vertically of the top, there is little or no possibility of the bunching of the yarn in the manner described.

In the operation of braiding machines, the yarn as it reaches the bottom of the cop, in its vertical run, is liable at times before changing from a downward to an upward movement, to drop below the bottom of the winding upon the cop, thus creating excessive slack, which must be taken up by the carrier. As this slack is taken up, the loose yarn below the winding is drawn toward the core of the cop and the spindle 14, and sometimes catches between the core of the cop and the top plate 11 of the base or the stud 32 projecting therefrom and serving as a support for said core. To obviate this condition, I provide means encircling and projecting above the bottom of the cop so that as the yarn in its run from the cop, approaches the bottom of the winding thereof, it will receive an upward lift sufficient to prevent the run of the lowermost part of the winding from the bottom of the cop downwardly. This means in the form of the invention shown, comprises a cup having a side flange 33 of a height to extend above the bottom of the cop to a limited extent. This cup is of a diameter to afford clearance between it and a cop of the largest diameter used. The bottom of the cup has a hollow nipple 34 adapted to embrace the support 32 or, if desired, the lower end of the core 15 of the cop. In this manner, particularly when the cop is at approximately its greatest diameter, the run of the yarn over the top edge of the side flange 33 will prevent falling of the yarn from the winding of the top in the manner above referred to.

In Fig. 5, I have shown a threading device used in drawing the yarn upwardly through the spring 28. This device consists of a length of wire 35 having at one end thereof, a hook 36 similar to that of a crochet needle. The wire is of a length

to permit it to be inserted through the lead-off eye 23 through and beyond the spring while exposing the end thereof above said eye to permit the withdrawal of the threading device from the spring during the threading operation.

5 The operation of the herein described carrier is substantially as follows:—

As is well known in the art, a braiding machine is equipped with a number of carriers and when 10 preparing for the run of a machine, the spindle 14 of each carrier has a cop mounted thereon. In mounting the cop, it is merely necessary for the operator to move the brake plate 31 outwardly against the tension of its spring and 15 mount the core 15 of the cop upon the spindle 14, the bottom of said core resting upon the support 32. The brake plate is then released and is engaged by its spring with the periphery of the 20 yarn upon the cop. The threading device 35 is then passed through the lead-off eye 23 with its hooked end 36 downward and the traveler 25 is raised against the tension of the spring 28 until it is positioned above the lower stop 21. The 25 looped end of the yarn is then passed through the elongated slot between the rods 18 and 19 above the stop 21 and below the traveler and engaged with the hooked end 36 of the threading 30 device. This device is then drawn upwardly carrying the yarn through the recessed portion 35 of the traveler through the coils of the spring 28 and outwardly of the lead-off eye 23. The traveler may then be released, the operator retaining control of the yarn beyond the lead-off eye 23.

35 During the operation of a braiding machine, movement of a carrier toward the braid being formed has a tendency to create slack in the run of the yarn between the carrier and the braid being formed. When tying in the end of the 40 yarn, the pull then raises the traveler 25 against the tension of the spring 28 by reason of the resistance offered to the turning movement of the cop by the brake plate 31. If the traveler is raised too high, there may be a turning movement imparted to the cop notwithstanding the 45 resistance of said brake plate.

The spring 28 being substantially in axial alignment with the lead-off eye 23 and extending over the recess 26 in the traveler, affords a clear path 50 for the run of the yarn from the traveler to said lead-off eye. The weight of the traveler and the action of the spring 28 do not exert a sufficient pull upon the yarn to impart any movement to the cop when the braiding machine is at rest, 55 such movement resulting only from the tensioning of the spring 28.

While a braiding machine is in operation, as 60 the carrier has movement toward the braid being formed, the slack between the carrier and the braid, representing yarn in excess of that incorporated in the braid due to the radial movement of the carrier, is taken up by downward movement of the traveler partly by gravity and partly by the expansion of the spring 28. With the 65 outward movement of the carrier, the traveler is raised and the yarn is tensioned, and the meshes of the braid closed by resistance to that upward movement of the traveler by the tension of the spring 28 and the resistance to the turning movement of the cop during the final stage of this upward movement.

The carriers move rapidly, and during upward movement of the traveler, its moving inertia or momentum, notwithstanding the resistance of the 70 spring which is not great, may pay out yarn so

rapidly as to create slack between the traveler and the lead-off eye. When the carriers are worn they are inclined to sway radially of the braid, and this swaying action may also create slack at the point mentioned. If this occurs, when two 5 carriers going in opposite directions are closely adjacent each other at the intersection of the two sinuous cam grooves, such slack, were it not for the telescopic member or spring 28, might, and sometimes did become entangled with parts of 10 the adjacent carrier, thus causing the breakage of the yarn thus entangled. The action of the traveler 25 and its spring 28, in addition to the functions already stated, limits the stresses applied to the yarn during the outward movement 15 of the carrier, and at the same time in conjunction with the means used to resist turning of the cop, ensures the application of the desired stresses. With increase in the tension of the spring 28, the resistance to the movement of the 20 traveler increases and when the spring has been tensioned to its full extent, the stress upon the yarn is increased as a result. This occurs when the bottom of the traveler approaches the stop bar 20, and the meshes of the braid are being 25 finally closed, and with greater uniformity in this action, the smoother will be the braid. The final closing of the meshes of the braid occurs while the cop is having movement, so that uniformity 30 in the quality of the braid is determined largely by the resistance to the cop movement.

By using an elongated slot in the upright there is no substantial variation in the resistance to the run of the yarn from the cop to the traveler, irrespective of the portion of the cop from which 35 the yarn is drawn. The upper stop 20 is so positioned that if the bottom of the traveler passes above same there will be increased resistance to the run of the yarn due to the friction resulting from the dragging of the yarn across this stop. 40

In a spirally wound cop, the point of the cop from which the yarn is being drawn varies constantly and extends from the extreme top to the extreme bottom of the winding of the cop. It is obvious that when the yarn is drawn from adjacent the top of the cop it passes downwardly to the traveler in passing through the slot adjacent the top thereof, and that when the yarn is being drawn from adjacent the bottom of the cop winding it will pass upwardly to the traveler 50 through the slot adjacent the bottom thereof. The angle of the yarn in relation to the traveler and to the cop will vary constantly, but there will never be any sharp bends in the yarn even when it passes about the traveler when the yarn is being drawn from adjacent the top or the bottom of the cop. This materially reduces the variation in the resistance to the run of the yarn and contributes toward a smoother braid. 55

During the movement of the carrier outwardly 60 of the braid, and while the traveler is approaching the uppermost limit of its movement, the stresses applied to the yarn impart turning movement to the cop. The brake plate 31 offers sufficient resistance to this turning movement to 65 avoid creation of slack between the traveler and the cop, and close the meshes of the braid as described. When a full cop is in position upon the carrier, the turning movement of the cop, when withdrawing yarn therefrom with each impulse, is short, and the friction developed by this turning movement, is low. Consequently, the form of the brake shoe is made such as to exert the greatest pressure against the cop throughout 70 the greatest contact area. 75

As the cop reaches its smallest diameter, the amount of movement of the cop with the withdrawal of the same amount of yarn will be more rapid and greater, and the friction developed will be proportionately higher. If the same contact area and the same pressure were maintained as to the brake plate, the resistance to the turning movement would be relatively greater than with a larger cop, since the movement of the cop is one factor in developing the friction for resisting turning of the cop. The reduced tension of the spring 30 and the increased radial distance of the contact area from the point of pivotal support of the plate will lower the resistance slightly, but I have found it desirable to also decrease the contact area since, in this manner, I can secure a closer approximation to a uniform resistance than if the lowering of the pressure and of the effective leverage of the brake plate were alone reliable.

When the yarn is being drawn from the extreme bottom of the cop, there is a tendency of the lowermost convolution thereof to slip from the cop, thus creating slack resulting in the dropping of the traveler and a momentary relieving of the stresses applied to the yarn in closing the meshes of the braid. The flange 33 of the cup is provided to prevent this. When the yarn is being drawn from this portion of the cup, it engages the top of the flange 33, this being a continuous circular flange. There is at this time, an upward pull on the yarn due to this engagement with said flange, which counteracts any tendency of the yarn to run below the winding upon the cop.

While the bottom of the cop is shown as being mounted upon the bearing 32, if desired it may be fitted directly to the core 15, and the height of the flange 33 may be proportioned to secure the desired lifting action upon the yarn.

With a carrier having an elongated slot as herein described, it is possible to use in a carrier, cops of considerably greater length than would otherwise be possible. The use of such cops is desirable because of the increased supply of yarn available, permitting a longer run of the braiding machine without stoppage for the replacement of cops.

By controlling the yarn in the manner herein described, breakage of the yarn, except from inherent defects therein, is prevented, and weak spots in the yarn, which under ordinary conditions will result in breakage, do not cause breakage where the stresses applied to the yarn are limited in the manner described.

While the spring 28 may bulge, the amount of lateral movement of the coils thereof is limited by the guide rod 24. Hence, while it is desirable to avoid such bulging, with a long spring it is sometimes unavoidable. This, however, will not interfere with the desired operation of the carrier.

By using round rods 18 and 19 and round stops 20 and 21, likelihood of abrasion of the yarn is practically eliminated.

It is not my intention to limit the invention to the precise details of construction shown in the accompanying drawing, it being apparent that such may be varied without departing from the spirit and scope of the invention.

Having described the invention, what I claim as new and desire to have protected by Letters Patent, is:—

1. A carrier for braiding machines embodying therein a base provided with a vertical spindle

adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for applying tensioning stresses to the yarn embodying therein a traveler slidably mounted upon said upright for movement along the portion of said upright having said elongated opening therein toward and from said lead-off eye about which the yarn passes in its run from said opening to said lead-off eye, and a collapsible confining member at one side of said upright, one end of which is engageable by said traveler, and the other end of which extends to adjacent said lead-off eye.

2. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for applying tensioning stresses to the yarn embodying therein a traveler slidably mounted upon said upright for movement along the portion of said upright having said elongated opening therein toward and from said lead-off eye about which the yarn passes in its run from said opening to said lead-off eye, a spiral spring at one side of said upright, one end of which is engageable by said traveler, and the other end of which extends to adjacent said lead-off eye and means preventing lateral bulging of said spring.

3. A carrier for braiding machines embodying therein a base provided with a vertical spindle adapted to have a cop rotatably mounted thereon, and means whereby travel may be imparted to the carrier, two vertically extending, rounded rods paralleling said spindle and each other, said rods being spaced from each other, and stops extending from rod to rod across the space between same to form an elongated opening therethrough for the run of the yarn, and a lead-off eye adjacent the top thereof, and means for controlling the run of yarn from the cop and for applying tensioning stresses to the yarn embodying therein a traveler slidably mounted upon said rods for movement along the portion of said upright having said elongated opening therein, toward and from said lead-off eye about which the yarn passes in its run from said opening to said lead-off eye, and a collapsible confining member at one side of said upright, one end of which is engageable by said traveler, and the other end of which extends to adjacent said lead-off eye.

4. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for applying tensioning stresses to the yarn embodying therein a traveler slidably mounted upon said upright for movement along the portion of said upright having said elongated opening therein toward and from said lead-off eye about which the yarn passes in its run from said opening to said lead-off eye, a collapsible confining member

at one side of said upright, one end of which is engageable by said traveler, and the other end of which extends to adjacent said lead-off eye, a curved brake plate engageable with the winding of the cop, a pivotal support therefor, and a spring operative upon said plate to engage it with the winding of the cop.

5. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for applying tensioning stresses to the yarn embodying therein a traveler slidably mounted upon said upright for movement along the portion of 10 said upright having said elongated opening therein toward and from said lead-off eye about which the yarn passes in its run from said opening to said lead-off eye, a collapsible confining member at one side of said upright, one end 15 of which is engageable by said traveler, and the other end of which extends to adjacent said lead-off eye, a curved brake plate engageable with the winding of the cop, a pivotal support therefor, and a spring operative upon said plate 20 to engage it with the winding of the cop, said plate being so formed as to progressively decrease the contact area between same and the cop winding with a lessening diameter of said winding.

35. 6. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for applying tensioning stresses to the yarn embodying therein a traveler slidably mounted upon 40 said upright for movement along the portion of said upright having said elongated opening therein toward and from said lead-off eye about which the yarn passes in its run from said opening 45 to said lead-off eye, and a spiral spring at one side of said upright, one end of which is engageable by said traveler, and the other end of which extends to adjacent said lead-off eye, whereby the run 50 of the yarn within said spiral spring and between said traveler and said lead-off eye is confined, and ballooning thereof is prevented.

55. 7. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for applying tensioning stresses to the yarn embodying therein a traveler slidably mounted upon 60 said upright for movement along the portion of said upright having said elongated opening therein, toward and from said lead-off eye about which the yarn passes in its run from said opening to said lead-off eye, a spiral spring at one side of said upright, one end of which is engageable by said traveler, and the other end of which 65

extends to adjacent said lead-off eye, whereby the run of the yarn within said spiral spring and between said traveler and said lead-off eye is confined, and ballooning thereof is prevented, and a guide rod paralleling said upright and inclosed within said spring.

70. 8. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for 10 applying tensioning stresses to the yarn embodying therein a traveler slidably mounted upon said upright for movement along the portion of said upright having said elongated opening therein toward and from said lead-off eye about 15 which the yarn passes in its run from said opening to said lead-off eye, a spiral spring at one side of said upright, one end of which is engageable by said traveler, and the other end of which extends to adjacent said lead-off eye, whereby 20 the run of the yarn within said spiral spring and between said traveler and said lead-off eye is confined, and ballooning thereof is prevented, and means preventing lateral bulging of said 25 spring.

30. 9. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, and means for controlling the run of yarn from the cop and for applying tensioning stresses to the yarn embodying therein a traveler slidably mounted upon 35 said upright for movement along the portion of said upright having said elongated opening therein toward and from said lead-off eye about which the yarn passes in its run from said opening to 40 said lead-off eye, a spiral spring at one side of said upright, one end of which is engageable by said traveler, and the other end of which extends to adjacent said lead-off eye, whereby the run 45 of the yarn within said spiral spring and between said traveler and said lead-off eye is confined, and ballooning thereof is prevented, and a guide rod paralleling said upright and inclosed 50 within said spring.

55. 10. A carrier for braiding machines embodying therein a base provided with a vertical spindle adapted to have a cop rotatably mounted thereon, and means whereby travel may be imparted to the carrier, two vertically extending rounded rods paralleling said spindle and each 60 other, said rods being spaced from each other, and stops extending from rod to rod across the space between same to form an elongated opening therethrough for the run of the yarn, and a lead-off eye adjacent the top thereof, and means for controlling the run of yarn from the cop and for applying tensioning stresses to the yarn embodying therein a traveler slidably mounted upon 65 said rods for movement along the portion of said upright having said elongated opening 70 therein toward and from said lead-off eye about which the yarn passes in its run from said opening to said lead-off eye, a spiral spring at one side of said upright, one end of which is engageable by said traveler, and the other end of which 75

extends to adjacent said lead-off eye, whereby the run of the yarn within said spiral spring and between said traveler and said lead-off eye is confined, and ballooning thereof is prevented, 5 and a guide rod paralleling said rods and in-closed within said spring.

11. A carrier for braiding machines embodying therein a base provided with a vertical spindle adapted to have a cop rotatably mounted thereon, and means whereby travel may be imparted to the carrier, an upright paralleling said spindle having a vertically elongated opening therethrough for the run of the yarn, and a lead-off eye adjacent the top thereof, means for 10 controlling the run of the yarn from the cop and for applying tensioning stresses to the yarn, embodying therein a traveler slidably mounted upon said upright for movement along the portion of said upright having said elongated opening therein toward and from said lead-off eye about which the yarn passes in its run from said opening to said lead-off eye, and a collapsible confining member at one side of said upright, one end of which is engageable by said 15 traveler, and the other end of which extends to adjacent said lead-off eye, and a cup having a continuous, circular flange extending about the bottom of the winding of the cop below the bottom of said elongated opening embodying there-

in means whereby it may be mounted in relation to the cup.

12. A carrier for braiding machines embodying therein a base provided with a vertical spindle adapted to have a cop rotatably mounted 5 thereon, and means whereby travel may be imparted to the carrier, an upright paralleling said spindle having a vertically elongated opening therethrough for the run of the yarn, and a lead-off eye adjacent the top thereof, means for 10 controlling the run of yarn from the cop and for applying tensioning stresses to the yarn embodying therein a traveler slidably mounted upon said upright for movement along the portion of said upright having said elongated opening therein toward and from said lead-off eye about which the yarn passes in its run from said opening to said lead-off eye, and a spiral spring positioned at one side of said upright, one end of which is engageable by said traveler, and the 15 other end of which extends to adjacent said lead-off eye, and a cup having a continuous, circular flange extending about the bottom of the winding of the cop below the bottom of said elongated opening embodying therein means 20 25 whereby it may be mounted in relation to the cup.

WILLIAM E. COOK.
